UNITED STATES PATENT OFFICE.

CHESTER H. SMITH, OF PITTSBURG, KANSAS.

HEADLAMP DEVICE.

Application filed March 31, 1925. Serial No. 19,677.

To all whom it may concern:

Be it known that CHESTER H. SMITH, a citizen of the United States, residing at Pittsburg, in the county of Crawford and 5 State of Kansas, has invented certain new and useful Improvements in Headlamp Devices, of which the following is a specification.

This invention relates to a head lamp 10 adapted to be worn upon the head of the user and being capable of a wide variety of uses.

It is a primary purpose of the invention to provide a lamp of the character described 15 having a wide range of adaptability as to the source of current supply and including in its make-up, elements adapted to be energized either from the ordinary 110 volt lighting circuits, such as are commonly 20 found in the offices of dentists, physicians and the like, or to be energized from the much lower voltage of automobile batteries so that it may be utilized as a trouble light. In either case the construction is such that 25 the light may be focused at the point where it is needed and neither the lamp nor the associated parts will heat up to such an extent as to burn or discommode either a patient or the operator coming into accidental contact therewith.

It is a further object of the invention to provide, in a device of this nature, an improved means for adjusting the reflector with respect to the light bulb said means 35 being of such a nature that the reflector may be adjusted to properly focus the light rays, with one hand, and will remain in such adjusted position without the manipulation of set screws or other fastening devices.

Further objects and advantages of the invention will be set forth in the detailed description which follows:

In the accompanying drawing: 45 Fig. 1 is a diagrammatic view illustrating the connections of the lamp.

Fig. 2 is a fragmentary side elevation illustrating the manner of mounting the lamp upon a head band.

50 Fig. 3 is a detail view of a universal connection hereinafter described.

Fig. 4 is a partial longitudinal sectional view through the structure of Fig. 2.

Like numerals designate corresponding parts in all of the figures of the drawing. 55

Referring to the drawing, 5 designates any suitable type of head band adapted to encircle the head of the user.

A universal joint by means of which the lamp may be bent at various angles and tipped to varying positions is formed by two spaced bars 6 and 7, which may be drawn toward each other by screw 8. The lower ends of these bars embrace a ball 10 that is carried by a plate 5^a. The upper ends 65 of the bars 6 and 7 receive between them a ball 12, constituting the terminal end of an arm 13, the latter constituting an extension of a sleeve 14, forming a part of a socket member having bayonet slots 15^a at one 70 end for the reception of a light bulb 16 and bayonet slots 17 at its other end for the reception of lugs 18 of a plug 19 of insulating material. A core 20 of insulating material carries the pins 21 and 22 contacting with 75 the terminals of the light bulb at one end and the terminals 23 and 24 of the plug 19. Electrical conductors 25 and 26 are connected to the contact points 23 and 24 and lead to a source of current supply as 80 hereinafter described. An ordinary 6-8 volt incandescent bulb 16 of the type commonly employed in automobile lamps serves as the source of illumination and the rear end of 85 this lamp is provided with laterally extending pins 16^a, engageable in the bayonet slots 15^a of the forward end of the socket member 14. This method of holding a lamp in place is quite well known in the automobile art and needs no further description. 90 A reflector 28 is provided with a sleeve 29 that is coarsely threaded upon a correspondingly coarsely threaded sleeve 29^a that is welded, soldered, brazed or otherwise secured in place on the socket member 14. 95 Thus by rotating it, the reflector may be adjusted with respect to the bulb to focus the light at the point where it is needed. This may be effected with one hand and such focus will be maintained without attention 100 upon the part of the user and without manipulating set screws or other fastening devices. This is of especial importance in dental and surgical work because it renders it possible for the operator to adjust the 105 position of the patient with one hand while

focusing the light with the other. Thus in dental work, for example, the patient's head may be turned or tipped to the most effective angle, simultaneously with the focusing of 5 the light.

In some classes of work, such as dental and surgical work, it is highly desirable to have the light focused upon a small area. In other classes of work it is desirable to 10 have the light diffused in such way as to illuminate a considerable area. This is particularly true when using the head lamp as a trouble lamp in the repair of automobiles on the road.

15 As is best illustrated in Fig. 1, the connections from the head band and lamp to the source of current supply, comprise a connection substantially like the base of the bulb and indicated at 30. In other words 20 this is a double contact connection to which the ends of conductors 25 and 26 are connected, the opposite ends of said conductors being connected to terminals 23 and 24 of plug 19. The connection is adapted to be inserted 25 in any of the light sockets of automobiles, such, for example, as the dash light socket and when plugged in at this point, the bulb 16 receives its source of current supply from 30 the storage battery of the automobile and the head lamp may be used as a trouble lamp in working about such automobiles. In addition, however, I provide a complementary connection element 30^a to co-act with the connection element 30 and serving to connect the 35 conductors 25 and 26 to conductors 33 and 34, said latter conductors receiving their current from an ordinary 110 volt lighting circuit 35, through the medium of an interposed variable transformer 36 by means of which 40 the current supply may be varied at will and the bulb 16 may be caused to burn brightly or dimly as desired.

Most of the head lamps on the market are 45 of fixed focus and practically all of them are constructed to be used with the ordinary 110 volt lighting circuits only. In other words the voltage of the bulbs used is fixed and the source of current supply is such as 50 to require the use of resistance elements which cause the lamp and associated parts to become so hot that patients have frequently been painfully burned by accidentally coming in contact with them. To the best of my 55 knowledge I am the first to provide a head lamp operable on such low voltages, without the use of resistance elements, as to provide a cool structure which cannot under any circumstances burn either the patient or the user; one which will be capable of being 60 focused to secure the best results, with one hand, and one which may be used either on a 110 volt lighting circuit or an ordinary automobile battery, or dry cell, circuit. When used as an automobile trouble lamp, 65 the device permits the free use of both hands

in working on the car, on the engine or in changing tires. The light is automatically thrown in the direction in which the eye or head turns.

I preferably make the reflector 28 of 70 ground glass having its rear surface silver plated. However, the construction of the reflector may be widely varied, since for cheaper constructions I may use a pressed nickel plated sheet metal plate. When the 75 glass reflector is used I provide an aluminum backing 37 of metal to protect the same.

While I have referred to the lamp as being of value to the physician, it is to be understood that I include in that term dentists, 80 obstetricians, gynecologists, eye, ear, nose and throat specialists, and all other having occasion to examine or treat living creatures.

I may employ a detachable connection 37 in the conductors 25 and 26 near the headband, so that the physician may, by disconnecting the conductors at this point, walk 85 freely about the room with the headband and light on his head and without the necessity of carrying either the transformer or a long 90 electric "cord".

The conductors 25 and 26 are preferably attached to band 5 by fabric loops 5^b. While I have referred to the band 5 as being of any suitable type, I preferably utilize the construction shown wherein a curved metallic plate 5^a is suitably slotted as at 5^c for the reception of a fabric web 5^d constituting the body of the band. A buckle is included in the length of the band. This construction 95 is not only very economical but it provides a structure that is light in weight and may be worn for extended periods without discomfort to the wearer.

It is to be understood that the invention is 105 not limited to the precise construction set forth but that it includes within its purview, whatever changes fairly come within either the terms or the spirit of the appended claim.

Having described my invention, what I claim is:

A device of the character described comprising a curved metallic plate having slotted portions, a headband having threaded 110 engagement in said slotted portions, a spherical element rigidly affixed to the headband, a lamp socket, an arm extending laterally from the lamp socket and rigidly affixed thereto and carrying a spherical element at 115 its end, a pair of spaced bars having semi-spherical recesses in their confronting faces receiving the spherical elements of the lamp and plate respectively to constitute a universal joint, a reflector and a threaded mounting 120 for said reflector with respect to the lamp socket.

In testimony whereof I affix my signature.

CHESTER H. SMITH.
